US0D1031888S

(12) United States Design Patent (10) Patent No.: US D1,031,888 S
Clarke et al. (45) Date of Patent:  Jun. 18, 2024

(54) GOLF CLUB HEAD

(71) Applicant: KARSTEN MANUFACTURING CORPORATION, Phoenix, AZ (US)

(72) Inventors: Jacob T. Clarke, Apex, NC (US);
Murphy R. Alexander, Scottsdale, AZ (US)

(73) Assignee: Karsten Manufacturing Corporation,
Phoenix, AZ (US)

() Term: 15 Years

(21) Appl. No.: 29/865,116

(22) Filed: Jul. 8, 2022

(51) LOC (14) Cl. 21-02

(52) U.S. Cl.

USPC D21/752

(58) Field of Classification Search

Primary Examiner — Mitchell I. Siegel

(57) CLAIM

The ornamental design for a golf club head, as shown and described.

DESCRIPTION

FIG. 1 is a top perspective view of a golf club head; FIG. 2 is a bottom perspective view of the golf club head of FIG. 1;

FIG. 3 is a top view of the golf club head of FIG. 1;

FIG. 4 is a bottom view of the golf club head of FIG. 1;

FIG. 5 is a front view of the golf club head of FIG. 1;

FIG. 6 is a rear view of the golf club head of FIG. 1;

FIG. 7 is a heel side view of the golf club head of FIG. 1; and,

FIG. 8 is a toe side view of the golf club head of FIG. 1. The broken lines shown on the drawings form no part of the claimed design.

1 Claim, 7 Drawing Sheets
